HAROLD C. EDDY, OF LOS ANGELES, CALIFORNIA, ASSIGNOR TO PETROLEUM RECTIFYING COMPANY OF CALIFORNIA, OF LOS ANGELES, CALIFORNIA, A CORPORATION OF CALIFORNIA

COMBINED WASHER AND DEHYDRATOR

Application filed December 7, 1929. Serial No. 412,400.

My invention relates to a novel washing device, and more particularly to a washing device which finds particular utility in direct or indirect combination with an electrical dehydrating apparatus.

It is old to introduce a fluid to be washed into a body of washing medium allowing the fluid to rise or fall through this medium to effect a washing thereof. Such a method is, however, open to objection inasmuch as the fluid to be washed forms a vertically moving stream through the washing medium. If the fluid is discharged from a nozzle, the stream thus formed is in the form of a vertical filament of the fluid which displaces a portion of the washing medium. The washing action is relatively limited due to the fact that the only contact between the fluid filament and the washing medium lies at the surface of the filament so that those particles of the fluid positioned in the center of the filament are not washed.

One way of securing a greater area of contact is to move the nozzle relative to the washing medium during the time that the fluid is being injected thereinto. If this nozzle is moved horizontally in a circular path, it is possible to form a cylindrical stream of the fluid which moves vertically through the washing medium, the diameter thereof being determined by the path of travel of the nozzle. Such a cylindrical sheet of fluid is much superior to the single fluid filament previously mentioned.

It is an object of this invention to provide a washing apparatus in which the fluid is introduced through one or more moving nozzles. A very definite channelling action takes place when a stationary nozzle is utilized, the fluid being discharged into the identical path followed by the fluid previously expelled. Similarly, with a moving nozzle which retraces its paths over a given cycle it is possible to complete this cycle before the fluid discharged on the previous cycle has had time to gravitationally move from the vicinity, thus forming a sheet of the fluid moving through the washing medium.

It is an object of this invention to provide a method and apparatus for washing a fluid

in a washing medium in which objectionable channelling action is greatly reduced and in some cases actually eliminated.

I have found that channelling is eliminated and a maximum washing action obtained if the movement of the nozzle is so slow that before the nozzle has time to complete a cycle, the fluid expelled therefrom on the previous cycle will have had time to gravitationally move from the vicinity of the nozzle, so that the channel previously formed is completely healed and the new fluid is therefore expelled from the nozzle into a continuous body of the washing medium, rather than being joined to the stream of fluid previously injected and it is an important object of the invention to provide an apparatus for accomplishing this end.

This method in effect forms a helical stream of the fluid in the washing medium if the nozzle is moving in a circular path, but it should be noticed that there is little or no tendency for any particle of the fluid to flow in the direction of the axis of this helical stream at any point and thus escape contact with the washing medium. This is because of the fact that the predominating tendency for such a particle of fluid is to move in a vertical direction. This tendency causes the helical stream of fluid to move vertically through the body of washing medium. Such a vertical movement of a sloping stream will continuously displace the washing medium through which the stream passes, thus not only offering infinitely more surface of contact between the fluid and the surrounding medium, but also setting up an agitation which I have found to be extremely desirable. The vertical channelling prevalent when the nozzle is stationary or when moved too fast is thus prevented.

It is an object of this invention to provide a method and apparatus for washing a fluid in a washing medium whereby the fluid rises through the medium in the form of a helix.

In addition, I have found it possible to greatly increase the washing action by using a rotatable spray means with the nozzles disposed at different radial distances from the axis of rotation thereof, and it is an object of

this invention to provide an apparatus where this increased action is present.

My washer finds particular utility in the field of electrical dehydration of petroleum emulsions for the purpose of removing water-rich masses from the oil emulsion, for the removal of colloidal matter, and the breaking up of loosely held emulsions before subjecting them to the action of the electric field, and for the purpose of illustration I shall disclose one type of apparatus which I have found very valuable for use in this art. This apparatus comprises a tank incorporating both the electrical dehydrating apparatus and the washing means, and certain features of this combination are in themselves novel and form a part of the present invention.

It is thus another object of this invention to provide a washing means which is novel both in itself and in combination with an electrical dehydrating apparatus.

Further objects and advantages of this invention will be evident hereinafter.

Referring to the drawings,—

Fig. 1 is a sectional view of a combined dehydrator and washing device of my invention.

Fig. 2 is a sectional view taken on the line 2—2 of Fig. 1.

Fig. 3 is an enlarged sectional view of the nozzle means disclosed in Fig. 1.

In the form of the invention shown in the drawings, I utilize a shell 10 closed at its upper and lower ends by a cover 11 and a bottom 12 respectively so as to form a tank 13. The interior of this tank is divided into a treating chamber 14 and a settling chamber 15 by a conical plate 16 extending across the tank with apex upward. This plate is slightly smaller in diameter than the inner diameter of the shell 10 so as to provide an annular space 18 therebetween, the plate 16 being supported by brackets 19 extending across this annular space and being secured both to the plate 16 and the shell 10.

Extending upward from the apex of the plate 16, and communicating with the settling chamber 15 is a central or primary electrode 20 in the form of a pipe, to the upper end of which is attached a nozzle 21 having a skirt 22 and extending downward around the electrode 20. The fluid to be treated rises through the electrode 20, as indicated by arrows 23, and passes through openings 25 formed in the electrode 20 inside the skirt 22 so that this skirt directs the fluid downward in the immediate vicinity of the central electrode 20, as indicated by arrows 26. A rod 27 tends to support the upper end of the electrode 20 and extends between the nozzle 21 and the cover 11.

Surrounding the central electrode 20 is a sleeve or secondary electrode 30 which cooperates with the primary electrode in defin-

ing a treating space 31. The sleeve electrode is mounted on rods 32 which extend into insulators 33, one of these rods being connected to the secondary of a high voltage transformer 34, the other terminal of this secondary being connected to the tank 13. A high potential electric field is thus set up in the treating space 31, this field being effective in agglomerating the dispersed phase of the emulsion rising through the central electrode 20.

If this emulsion is of the water-in-oil type, the water particles agglomerate and gravitationally separate from the dry oil, this dry oil moving upward into the upper portion of the tank 13 and being removed through a pipe 35. The agglomerated water particles drop downward onto the upper surface of the plate 16 whence they are guided through the annular passage 18 and into the settling chamber 15.

This water which is separated from the emulsion forms a body of washing medium, the upper surface of which is indicated by the line W—W of Fig. 1. This level may be visually indicated by the usual level-indicating gauge 38 communicating with the interior of the tank 13 at points above and below the desired level. This level is controlled by the amount of water withdrawn through a pipe 39 communicating with the lower portion of the settling chamber.

The emulsion to be treated is introduced into the tank 13 through a pipe 40 extending thereinto and providing a vertical leg 41 to which is journaled a pipe 42 connected to a spray means 43. This spray means is below the level W—W and includes one or more arms 44, each of which is in communication with the interior of the pipe 42 so that the emulsion supply thereto is equally distributed to each of the arms 44.

Each arm carries one or more nozzles 45 and if a plurality of arms is utilized, the nozzles on each arm are disposed at different radial distance from the axis of the pipe 42. In the ordinary size of tank I have found it possible to utilize a plurality of nozzles on each arm, as shown for instance in Fig. 2. It will be noted that each of the nozzles 45 is directed tangentially so that the emulsion forced through the pipe 40 exerts a reaction on the spray means 43 tending to rotate this means in a direction indicated by the arrow 49 of Fig. 2. The speed at which this spray means turns is controlled by a pressure-control valve 50 in the pipe 40.

In first starting the operation of the treater, it is usually desirable to fill the tank to the level W—W with water and the remaining portion of the tank with dry oil. The emulsion is then forced through the pipe 40 and is discharged into the body of washing medium by means of the nozzles 45. The speed of rotation of the spray pipe is so regu-

lated that the stream formed by any particular nozzle during one revolution will have moved upward in the body of washing medium a sufficient distance so that the new fluid introduced at this point on the subsequent revolution will not be introduced into the same stream previously formed. In other words, each nozzle 45 forms a helical stream of the fluid to be washed in the body of washing medium, and the "lead" of this helix is sufficient so that adjacent sections of the stream are separated by a body of the washing medium. A similar concentric helix is formed by each of the nozzles 45 and all of the helices move upward through the body of washing medium in spaced relationship, the emulsion being thoroughly washed and rising toward the apex of the plate 16.

From here the emulsion rises through the central electrode and is discharged into the treating chamber as previously described, the water particles being therein agglomerated after which they drop to the settling chamber 15 and serve to renew the supply of washing medium in the lower portion of the tank 13, the excess amount of washing medium being drawn off through the pipe 39.

While I have shown my settling device in combination with the electrical dehydrator, it should be clear that I am not limited to this particular embodiment. It is entirely possible, and in certain instances desirable, to position the dehydrating apparatus in a tank separate from the tank enclosing the washing apparatus of my invention. Furthermore, the washing means is not limited to use with electrical dehydration apparatus nor with the treated or untreated products used or formed therein, but is also applicable to any washing action wherein a fluid is to be washed by a washing medium.

I claim as my invention:

1. In combination: a tank; a plate extending substantially across said tank and dividing the interior thereof into a treating chamber and a settling chamber in communication through an annular space around said plate; means for establishing an electric field in said treating chamber; passage means for conducting fluid from the top of said settling chamber into said treating space, a portion of said fluid falling, after treatment, to said settling chamber to form a stratified body of washing medium; and means for introducing the fluid to be treated into said settling chamber below said body of washing medium, said fluid to be treated rising therethrough and being conducted into said electric field through said passage means.

2. In combination: a tank; a plate extending substantially across said tank and dividing the interior thereof into a treating chamber and a settling chamber in communication through an annular space around said plate; a primary electrode extending upward from

said plate and communicating with the settling chamber therebelow; a secondary electrode adjacent said primary electrode and cooperating therewith in defining a treating space; nozzle means on said primary electrode for introducing fluid from said settling chamber into said treating space where it is subjected to an electric field, a portion thereof dropping to said settling chamber to form a body of washing medium; and means for introducing the fluid to be treated into said settling chamber below said body of washing medium.

3. A method of washing a fluid of one density in a washing medium of another density, which includes the step of: introducing said fluid into said washing medium in the form of a helical filament which moves through the washing medium due to the difference in density between said fluid and said washing medium.

4. A method of washing a fluid of one density in a washing medium of another density, which includes the steps of: introducing said fluid into said washing medium through a nozzle; moving said nozzle through a closed path to discharge a stream of said fluid into said washing medium; and regulating the speed of movement of said nozzle so that streams of said fluid discharged from said nozzle on successive movements through said closed path are separated by a portion of said washing medium rather than joining together to effect a channelling action.

5. A combination as defined in claim 1 in which said passage means comprises an electrode which cooperates in forming said electric field.

In testimony whereof, I have hereunto set my hand at Los Angeles, California, this 3rd day of December, 1929.
